CLAIM

The ornamental design for a sample materials container for medical or laboratory purposes as shown and described.

DESCRIPTION

1. Sample materials container for medical or laboratory purposes

1.1 : Perspective

1.2 : Front

1.3 : Back

1.4 : Left

1.5 : Right

1.6 : Top

1.7 : Bottom

Figure 1.1 is a perspective view showing our new design; figure 1.2 is a front elevation view thereof; figure 1.3 is a rear elevation view thereof; figure 1.4 is a left side elevation view thereof; figure 1.5 is a right side elevation view thereof; figure 1.6 is a top plan view thereof; and figure 1.7 is a bottom plan view thereof.

(Continued)

The broken circular line and the area enclosed by the broken circular line in figure 1.7 are for illustrative purposes only and form no part of the claimed design.
